UNITED STATES PATENT OFFICE.

WILLIAM T. BLANEY, OF WINDSOR, ONTARIO, CANADA.

STREET-SWEEPING MACHINE.

1,209,384.

Specification of Letters Patent. Patented Dec. 19, 1916.

Application filed August 20, 1915. Serial No. 46,430.

To all whom it may concern:

Be it known that I, WILLIAM T. BLANEY, a subject of the King of Great Britain, residing at Windsor, in the county of Essex, Province of Ontario, Canada, have invented certain new and useful Improvements in Street-Sweeping Machines; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to street sweeping machines of the motor-driven vehicle type, and consists in the novel features of construction and operation as hereinafter set forth and claimed.

The principal object of the invention is the provision of an efficient power driven tractor-drawn street sweeping machine, wherein a single rotary brush is employed as the sweeping means, and which is so supported within the machine and connected in driving engagement with power transmitting means positioned upon one side thereof (preferably the left-hand side of the vehicle) as to leave the opposite side free from obstructing projections and permit the working of the end of the brush in close proximity to the curb of the roadway to enable the removal of the dirt from the gutter without necessitating the employment of an auxiliary or gutter brush.

Further objects are sought through the provision of means for wiping the brush to insure the discharge of the dirt therefrom onto a conveyer by which it is elevated and stored within the body of the machine; of means for inducing an air draft by suction to prevent the spreading and escape of dust produced by the action of the brush, and for drawing it into the housing of the machine, and of means through which the dust laden air may be circulated to extract and collect the dust therefrom and release the filtered air to the atmosphere.

The above objects are attained by the employment of the construction and association of parts as illustrated in the accompanying drawings, in which,

Figure 1 is a side elevation of the com-

pleted machine embodying my improved features coupled to a front wheel driven tractor by which it is drawn, showing the right-hand or curb-side of the machine, and indicating by dotted lines the power transmission to the operative parts. Fig. 2 is a sectional side elevation of the body of the machine having the lower half of the side broken away to show the interior arrangement of the parts. Fig. 3 is a transverse horizontal sectional view through the body of the machine on irregular dashed line 3—3 of Fig. 2. Fig. 4 is a front end sectional elevation having the lower portion of the end wall and inner vertical partition broken away to show the arrangement of the motive power and driving connections. Fig. 5 is a rear end elevation of the machine.

Referring to the parts of the device by the characters of reference indicating the parts throughout the several views of the drawings, 1 designates a rectangular body or housing containing the operative parts of the machine, which is carried on a frame 2 supported at the rear end upon springs 3 mounted on an axle 4 having transporting wheels 5 thereon, and is connected to and supported at its forward end upon a self-contained power driven tractor 6 having combined driving and steering wheels 7 by which the machine is drawn and its course is directed, as shown in Fig. 1.

The forward lower portion of the housing 1 is extended downwardly to a point in close proximity to the road surface, and the bottom of this portion is provided with an inlet opening in which a rotary sweeping brush 8 is mounted to operate between the side walls of said housing. A vertical partition 9 extending from the forward edge of this opening forms in conjunction with a horizontal partition 10 within the housing a main compartment or chamber 11 and a forward chamber 12, in the latter of which the motive means for driving the operative parts is contained and comprises an engine or motor 13 mounted at one side therein on a sub-frame 14 and connected at one end of its shaft 15 through a sprocket wheel 16 and chain belt 17 thereon with a sprocket wheel 18 on the shaft 19 of a blower or exhaust fan 20 supported in the opposite side of said chamber, the relative diameters of the sprockets 16 and 18 being such as to drive the

fan at a higher speed than that of the motor. (See Figs. 2 and 3). The opposite end of the motor shaft 15 extends through the side wall of the housing and carries a sprocket wheel 21 from which a chain belt 22 leads to a larger sprocket wheel 23 on the end of the shaft 24 of the rotary brush 8, by which said brush is rotated at the desired speed and in reverse direction to its forward travel upon the surface of the roadway.

The shaft 24 is journaled at opposite ends in bearing boxes 25 mounted to slide vertically in the arc of a circle, of which the motor shaft forms the center, in U-shaped guide ways 26 formed in the lower edges of the side walls of the housing and which permit said brush to rise and fall in maintaining peripheral contact with the uneven surface of the roadway. Suitable provision is made but not shown herein by which the brush may be raised and retained clear of the road surface when desired, as is common practice in operating brushes in street sweeping machines.

A chain belt conveyor 27 for elevating and storing within the housing the heavier particles of dirt and dust raised by the brush is rearwardly inclined with its lower end positioned adjacent the periphery of the brush at the rear side thereof and with its upper end extending rearwardly into the chamber 11 of said housing. The lower end of this conveyor is carried on sprockets 28 mounted on a transverse shaft 29 journaled in bearings 30 through the side walls of the housing, and is carried at its upper end on sprockets 31 secured on a transverse shaft 32 journaled through the side walls of the housing in bearings 33. The conveyor is driven by a chain belt 34 leading from a sprocket wheel 35 on the end of the shaft 32 to a sprocket wheel 36 on a countershaft 37 which is journaled through the side wall of the housing in a bearing 38 and carries on its inner end a gear wheel 39 meshing with a pinion 40 on the engine shaft 15, as clearly shown in Fig. 4. By this arrangement the motion imparted to the conveyor is such as to cause the lower lead of its chain belt to travel upwardly, and located beneath this side of the belt is an inclined wall or table 41 which extends the full width of the housing and is turned outwardly and rearwardly into the chamber 11 at its upper end and is curved forwardly and upwardly at the lower end concentric with the shaft 29 of the conveyor and terminates in an outwardly turned lip 42 adjacent the brush in line with the inlet opening of the housing. The lower upturned edge of this table forms a trough-like receptacle for the dirt delivered from the brush and contacts throughout its upper face with the blades or scrapers of the conveyor by which the dirt is

elevated and discharged rearwardly into the 65 chamber 11. (See Fig. 2.)

To facilitate the gathering of the dirt by the brush and to control the discharge therefrom so as to cause the bristles of the brush to expel the dirt and direct its delivery into the trough of the table of the conveyor, an up-curved sheet metal hood 43 is mounted over the upper forward portion of the brush in spaced relation thereto and is secured at its end walls 44 to ears 44' on the corresponding bearing boxes 25 at opposite ends of said brush by which it is supported to move vertically therewith. A flexible apron 45 is attached to the lower forward edge of the hood 43 and trails upon the road surface in advance of and at an incline to the brush, serving as a guard to deflect the dust upwardly into the hood in the direction of rotation of said brush, and hinged at one edge to the upper forward edge of the hood 85 and engaging at its free edge with the periphery of the brush is a wiping strip 46 which is yieldably held in contact therewith by curved leaf-springs 47 secured at one end to the said hood and bearing at their free 90 ends upon the upper face of said strip in advance of its hinged edge, as shown in Figs. 2 and 3, whereby the dirt raised by the brush will be carried upwardly within the hood and as the bristles of the brush 95 encounter and pass the forward edge of the wiping strip they will be successively retarded and abruptly released in a manner to impel the dirt carried thereby tangentially from the brush and deposit it upon 100 the table and into the trough of the conveyor by which it will be elevated and dumped into the rear of the chamber 11. An opening having a hinged closure 48 in the rear end wall of the housing affords 105 means through which the accumulation of dirt may be discharged.

As a means for preventing the spreading and escape of the dust raised by the motion of the brush and to insure the gathering of the lighter particles that may be released by the bristles on the down travel side of the brush to prevent their deposit on the road surface, a suction conduit 49 is formed between the under face of the table 41 and an outer wall 50 which extends the full width of the housing, conforming to the under face of said table and having an inlet throat or opening in the lower end thereof in line with the lower end of said table. The lower end of the wall 50 is provided with a hinged shield or apron 51 which depends to close proximity with the road surface, and the upper end of the wall extends into the chamber 11 and is returned 120 upon the under face of said table and closes the upper end of said conduit. A vacuum tendency is induced in the conduit 49 and

also in the chamber 11 by suction through a horizontal conduit 52 which is disposed exteriorly of the housing and communicates through the side wall thereof at one end 5 with said suction conduit and with said chamber through a lateral inlet port 53 and at its opposite end with the intake side of the exhaust fan 20, by means of which an air draft is created through the throat of 10 said conduit and through said inlet port to draw the dust from the road surface and opening around the brush and from the chamber above the brush into the fan. The dust is then conducted through a vertical 15 conduit 54 communicating at its lower end with the discharge outlet of the fan and at its upper end with a horizontal conduit which communicates with a receiving chamber above the horizontal partition 10 of the 20 housing, wherein it is distributed and circulated through separating and collecting means by which the dust is extracted and accumulated and the clarified air is discharged into the atmosphere.

25 The dust separating and collecting means above referred to and indicated by dotted lines in Fig. 2, comprises the subject matter of a separate application for patent filed herewith and need not be herein described 30 in detail, as it forms no part of the present invention. Any other suitable dust separating means may be employed in connection with the sweeping and suction inducing means, the arrangement and association of 35 which constitute the principal features of this invention.

From the foregoing description the operation of the machine will be readily understood, it is thought, without further stating 40 its action in detail, other than to point out that by reason of the relation, arrangement and coöperation of the brush, conveyer and suction throat the machine is rendered so efficient for dry sweeping as to insure the 45 removal of both dirt and dust in a manner to leave the road surface comparatively clean and the air free from dust after the passage of this machine.

While I have shown and described a preferred form of construction, the invention is presented as including all such changes or modifications as come within the scope and meaning of the following claims.

I claim:

55 1. In a street sweeper, a vehicle frame, a housing mounted on said frame and having a storage chamber provided with an inlet opening, a rotary brush in said opening journaled in bearings mounted to move 60 up and down in the arc of a circle in the sides of said housing, a hood carried by said bearings and overlying the upper forward portion of said brush, a wiping strip hingedly connected to the forward edge of

said hood and yieldably engaging the periphery of said brush, and an inclined table having its lower end adjacent said brush and adapted to receive the sweepings discharged therefrom. 65

2. In a street sweeper, a vehicle frame, a 70 housing mounted on said frame and having a storage chamber provided with an inlet opening, a rotary brush in said opening journaled in bearings mounted to move up and down in the arc of a circle in the sides 75 of said housing, a hood carried by said bearings and overlying the upper forward portion of said brush, an upwardly inclined table having an upturned trough at its lower end adjacent said brush and adapted 80 to receive the sweepings therefrom, and a conveyer mounted above said table and adapted to convey the sweepings from said trough into said storage chamber.

3. In a street sweeper, a vehicle frame, a 85 housing mounted on said frame and having an inlet opening therein, a rotary sweeping brush mounted in said opening, an inclined table mounted in said opening and forming at its lower end an up-turned trough adjacent 90 said brush to receive the sweepings discharged thereby, a suction conduit formed in conjunction with the under face of said table and having an inlet throat beneath said trough to receive the dust raised by 95 said brush, a conveyer mounted above said table and associated with said trough for conveying the sweepings therefrom, means for operating said brush and conveyer, and means for inducing suction in said conduit 100 to draw the dust from about said trough.

4. In a street sweeper, a vehicle frame, a housing mounted on said frame and having a storage chamber provided with an inlet opening, a sweeping brush mounted to rotate in said opening, an inclined table mounted in said opening to extend into said storage chamber and forming at its lower end an up-turned trough adjacent said brush to receive the sweepings discharged 105 therefrom, a suction conduit formed on the under face of said table and having an inlet throat conforming with said trough and opening at the edge thereof adjacent said brush to receive the dust raised thereby, 110 means for directing the delivery of the sweepings from said brush toward said trough and throat, means for conveying the sweepings from said trough into said storage chamber, and means for inducing suction in said throat to draw the dust from about said trough and brush. 115

5. In a street sweeper, a vehicle frame, a housing mounted on said frame and having a storage chamber provided with an inlet 120 opening, a rotary sweeping brush mounted in said opening, an inclined table formed to provide an upturned trough at its lower 125

end adjacent said brush to receive the sweepings discharged therefrom, a suction conduit extending across the under face of said table and having an inlet throat ⁵ forming with said trough and opening at the lower edge thereof adjacent said brush to receive the dust raised thereby, a connecting conduit communicating with said suction conduit and having an inlet port

communicating with said storage chamber ¹⁰ above said brush, means for conveying the sweepings from said trough into said storage chamber, and means for inducing suction in said conduits to draw the dust from about said brush. ¹⁵

In testimony whereof, I sign this specification.

WILLIAM T. BLANEY.
